UNITED STATES PATENT OFFICE.

ARTHUR E. PEW, JR., OF BRYN MAWR, PENNSYLVANIA, ASSIGNOR TO SUN OIL COMPANY, OF PHILADELPHIA, PENNSYLVANIA, A CORPORATION OF PENNSYLVANIA.

MINERAL-OIL VAPORIZER.

Original application filed June 19, 1925, Serial No. 38,184. Divided and this application filed February 27, 1926. Serial No. 91,045.

In an application filed by me June 19, 1925, Serial No. 38,184, of which this application is a division, I set forth an apparatus for the continuous distillation of oil under a high 5 vacuum. Included in the apparatus is a series of stills in each of which is a vaporizing pan that receives oil admitted to the still and extends through the still in an inclined direction over the body of oil in the still. Part of 10 the oil that travels along the pan is vaporized. The unvaporized residue is discharged into the body of oil in the still.

The invention forming the subject matter of this patent comprises the construction and 15 arrangement of this vaporizing contrivance.

A preferred embodiment of the invention is shown in the drawings, in which—

Fig. 1 is a longitudinal section through the still with the internal reinforcing elements 20 in part omitted to enable the vaporizing pan to be properly illustrated.

Fig. 2 is an enlarged end view of the distributing box and the connections therefrom to the vaporizing pans.

Fig. 3 is a side elevation of the parts shown 25 in Fig. 2.

Fig. 4 is a plan view of the parts shown in Fig. 2.

From the source of supply (which will be 30 from a preceding still unless the tank is the first of the series) the oil is admitted through a pipe *b* to a distributing box *c* in the upper part, and at one end, of the cylindrical distilling tank *a*. Box *c* has two partitions *d*, *d*, 35 extending lengthwise of the tank and of less height than the side walls of the box. These partitions form a central chamber *e* and two side chambers *f*, *f*. The oil is admitted to the central chamber and there, by overflowing the partitions, equally distributes itself into the two side chambers. From the side chambers 40 the oil flows laterally, through pipes *g*, *g*, into the upper ends of two long vaporizing pans *h*, *h*. A short distance from its upper end 45 each pan is provided with a weir *i*, the space back of the weir forming a secondary feed box *j*. Weir *i* has a corrugated or notched upper edge, over which the oil flows into the pan *h*, which extends nearly the length of the 50 still and down which the oil flows and from the lower end of which the unvaporized residue discharges into the body of oil in the still.

The oil, in flowing down these pans, spreads over a large surface in a thin layer.

This greatly expedites the rate of evaporation. Further, intimate contact is effected between the flowing sheet of oil and the hot vapors from the body of oil in the still. Further, the thin sheet of oil is in contact throughout its entire area with hot metal, 60 between which and the oil is a rapid exchange of heat.

It has been found, in the operation of stills equipped with these vaporizing pans, that there is danger, due to the foaming of the oil, 65 of fine particles of oil becoming entrained with the light vapors that alone should theoretically be driven off at the still temperature. Foaming is minimized and such danger obviated by enclosing the space immediately above the pan with a fine screen *m*. A similar screen *n* covers the distributing box *c*.

The vapors evaporated from the pan *h* escape through openings arranged along the top of the tank *a* into pipes extending to a 75 condenser (not shown). It is important that the vapors leaving the still shall not contact with the oil admitted to the still.

I claim—

1. The combination, with an elongated still 80 chamber, of an inclined oil vaporizing pan extending longitudinally therein, means to supply oil to the upper end of the pan, and a reticulated cover overlying the pan, the openings formed by the reticulated cover being in free communication with the chamber space outside the cover, thereby allowing free escape of oil vapors while minimizing foaming of the oil and escape of liquid particles with the oil vapors from the oil stream during 85 the flow of the oil along the pan.

2. The combination, with an elongated still chamber, of an oil distributing box therein, means to supply oil thereto, two inclined vaporizing pans extending longitudinally 95 through the still chamber, the upper ends of the pans being on opposite sides of, and adapted to receive oil from, said box, and reticulated covers overlying the distributing box and the pans, the openings formed by the 100 reticulated cover being in free communication with the chamber space, thereby allowing free escape of oil vapors while minimizing foaming of the oil and escape of liquid particles with the oil vapors from the body of the oil in the distributing box and from the oil stream flowing along the pans.

3. The combination with an elongated still

chamber, of a primary oil distributing box therein, overflow partitions therein forming a central oil receiving compartment and side oil discharge compartments, means to supply 5 oil to the central compartment, secondary feed boxes arranged to receive oil from the respective side oil discharge compartments, the front wall of each secondary feed box

forming a weir, and two inclined vaporizing 10 pans with smooth and uninterrupted flow surfaces extending from the respective weirs longitudinally through the still chamber.

In testimony of which invention, I have hereunto set my hand, at Philadelphia, Penna.. on this 19th day of February, 1926.

ARTHUR E. PEW, JR.

CERTIFICATE OF CORRECTION.

Patent No. 1,700,709.

Granted January 29, 1929, to

ARTHUR E. PEW, JR.

It is hereby certified that the State of Incorporation of the assignee in the above numbered patent was erroneously given as "Pennsylvania", whereas said State should have been given as "New Jersey", as shown by the records of assignments in this office; and that the said Letters Patent should be read with this correction therein that the same may conform to the record of the case in the Patent Office.

Signed and sealed this 19th day of February, A. D. 1929.

(Seal)

**M. J. Moore,
Acting Commissioner of Patents.**
